UNITED STATES PATENT OFFICE

91,888

DESIGN FOR A LAMP SHADE

Morris A. Kremer, Far Rockaway, N. Y., assignor to East Side Metal Spinning & Stamping Corp., New York, N. Y., a corporation of New York

Application January 25, 1934, Serial No. 50,503

Term of patent 7 years

To all whom it may concern:

Be it known that I, MORRIS A. KREMER, a citizen of the United States and a resident of Far Rockaway, county of Queens, State of New York, have invented a new, original, and ornamental Design for Lamp Shades, of which the following is a specification, reference being had to the accompanying drawing, forming part thereof, wherein

Fig. 1 is a front elevation,

Fig. 2 a top view and
Fig. 3 a side view of a lamp shade embodying my invention.

I claim:

The ornamental design for a lamp shade, as shown.

MORRIS A. KREMER.
